WRINGER

Walter L. Kauffman, II, Erie, Pa., assignor to
Lovell Manufacturing Company, Erie, Pa., a
corporation of Pennsylvania

Original application July 11, 1932, Serial No.
621,921. Divided and this application October
19, 1938, Serial No. 235,877

6 Claims. (Cl. 68—263)

Power wringers are usually provided with safety releases by means of which the pressure on the rolls may be immediately released when the operator is caught in the rolls, or the clothes are carried around the rolls. The present invention is designed to improve safety release devices and to that end provides a trip bar across the wringer which may be readily operated to effect the release. The present invention contemplates also a very simple mechanism in which the movement of the bars is very directly communicated to the release mechanism so that a very sensitive release may be accomplished. The invention also involves the simplification of the mechanism. Features and details of the invention will appear from the specification and claims.

The present application is a division of an application filed July 11, 1932, Serial No. 621,921.

A preferred embodiment of the invention is illustrated in the accompanying drawing as follows:

Fig. 1 shows a front elevation of the wringer partly in section showing the invention.

Fig. 2 a section on the line 9—9 in Fig. 3.

Figs. 3 and 4 end views of the upper part of the wringer.

Fig. 5 a perspective view of catch plates forming a part of the releasing mechanism.

1 marks the base of the wringer frame, 2 the side stiles, 3 and 4 the wringer rolls, 5 and 6 the shafts of the rolls, and 7 and 8 bearings of the rolls. The bearings are mounted as usual in the stiles. A top bar 9 is of channel form with closed ends which telescope over the upper ends of the stiles. A spring 10 provides pressure means for the rolls, the ends of the spring resting on the upper bearings 8 and the center of the spring being subjected to the action of an adjusting screw 11.

Catch plates 12 are arranged at each side of the upper ends of the top stiles. The catch plates at the opposite sides are united by a cross plate 13. The catch plates have pivot openings 14 and lips 15 struck up from the side stiles extending through these openings forming a pivotal connection for the catch plates.

A release lever 16 is arranged over the end of the top stile. It has downwardly extending flanges 17 at each side of the top bar. Lips 18 are arranged along the lower edges of the flanges 17 and these lips are provided with pivot extensions 19 which extend through pivot openings 20 in the side walls of the top bar. The catch plates 12 have hooks 21 which lock on the lips 18 to hold the top bar in normal position and

thus sustain the pressure of the spring. A spring 22 is arranged between the release lever 16 and the top plate and tends to hold the release lever in position to retain the hooks 21. Shoulders 24 are arranged on the locking plates and engage the outer ends of the lips 18 when the release lever is in normal position. Thus the accidental release of the catch plates is avoided, the catch plates being locked in position by the shoulders 24 until the outer end of the lever is 10 raised.

A rocker 38 is pivotally mounted on the upper part of one of the side stiles. It is directly pivoted on a spacing bushing 39 mounted on a screw 40, the spacer being clamped by a nut 41 15 acting on a washer 41a. The rocker has a trip extension 42 which projects outwardly beyond the latch plates 12 and is provided with an in-turned lip 43 which is directly under the end of the release lever 16. The trip bars, or operating bars 44 are secured to the rocker 38 and extend across the upper part of the wringer and in front thereof. Preferably these rods extend up sufficiently so that the operator can thrust against them with the open hand pushing the 25 rods toward the top bar. The opposite ends of the rods are secured in rocker arms 45 secured on a pivot 46, the details of the pivot being similar to those securing the rocker 38.

In the operation of the device when the operator swings in either trip bar 44, this swings the front, or rear edge of the rocker plate 42 toward the center and this edge moves on an arc with the pivot of the rocker 38 as a center, thus lifting the end of the release lever 16 and 35 this lifting of the lever lifts the lip 18 out of engagement with the shoulder 24 and permits the latch plate to slide off the lip 18 and release the top bar.

The release is effected both from a push or a 40 pull of the trip rods toward or from the face of the wringer frame or up and down, and the release is effected with equal sensitivity at any part of the trip bar. The trip bars give more than a single target as a place for the operator to hit. This is important in that this operation is only utilized under panic conditions. The bars extend in a direction parallel to the rolls and maintain this parallel relation as they are rocked.

The opposite end of the top bar has a lip 47 which forms a shoulder 48. A similar lip 49 is struck up in the stile, this lip forming a shoulder engaging the shoulder 48. Thus the top bar is locked against upward movement until the 55

latch end of the top bar is released, the latch end then swinging upwardly on the shoulders as a hinge and this is followed by the disengagement of the shoulders making a full release of the pressure on the rolls.

5. What I claim as new is:

1. In a wringer having a frame with stiles, rolls mounted in the frame, pressure means for the rolls, and a safety release device comprising

10 a trip bar extending parallel to the wringer adjacent to the top of the wringer; the combination with the safety release device of trip arms on which the bar is mounted, said arms having pivots mounted on the upper parts of the stiles

15 below the trip bar and with axes parallel with the rolls; and means responsive to a pivotal movement of said bar releasing the pressure means.

2. In a wringer having a frame with stiles, rolls mounted in the frame, a top bar, pressure means

20 for the rolls exerting pressure from the top bar, and a safety release comprising a latch mechanism between the top bar and the upper end of a stile; the combination with the safety release device of a trip bar parallel to the frame pivotally mounted on the stiles with a pivot below the trip bar and operating the latch mechanism.

3. A roll wringer releasing device comprising a rigid wringer frame, parallel rolls, and pressure means to urge the rolls toward each other, the

30 combination with the frame of a trip bar parallel to the rolls and sensitive to horizontal pressure toward the frame; means on the rigid frame below the top thereof movably supporting the trip bar; and mechanically actuated means making

35 the trip bar effective to release the pressure means when the trip bar is moved while remaining parallel to the wringer rolls.

4. A roll wringer releasing device comprising a wringer frame with stiles, parallel rolls, and

40 pressure means to urge the rolls toward each

other, the combination with the frame of a trip bar parallel to the rolls and sensitive for release to initial upward pressure and also to initial downward pressure; means on the frame stiles below the top thereof movably supporting the trip bar; and mechanically actuated means making the trip bar effective to release the pressure means when the trip bar is moved while remaining parallel to the wringer rolls.

5. A roll wringer releasing device comprising 10 a wringer frame with stiles, parallel rolls, and pressure means to urge the rolls toward each other; the combination with the frame of a trip bar parallel to the rolls and sensitive for release to initial, horizontal pressure and also to initial 15 downward pressure; means on the frame stiles below the top thereof movably supporting the trip bar; and mechanically actuated means making the trip bar effective to release the pressure means when the trip bar is moved while remaining 20 parallel to the wringer rolls.

6. A wringer comprising a frame having separable sections, the bottom section being rigid and having side stiles and a base, wringer rolls journaled in the frame, pressure means for applying 25 pressure to the wringer rolls when the frame sections are operatively connected, and a safety release device connecting the sections for maintaining the wringer rolls under pressure; the combination with said frame sections of a trip 30 bar parallel to the rolls and sensitive to horizontal pressure toward the frame; means on the lower section of the rigid frame movably supporting the trip bar; and mechanically actuated means making the trip bar effective to 35 release the upper section and thus release the pressure on the rolls when the trip bar is moved while remaining parallel to the wringer rolls.
